UNITED STATES PATENT OFFICE.

HERSHEL A. BENEDICT, OF EAST ORANGE, AND EDWARD M. MOLLER, OF JERSEY CITY,
NEW JERSEY.

UNDERHANG FRAMEWORK OR CHASSIS CONSTRUCTION.

1,387,757.

Specification of Letters Patent. Patented Aug. 16, 1921.

Application filed February 7, 1920. Serial No. 356,888.

To all whom it may concern:

Be it known that we, HERSHEL A. BENEDICT and EDWARD M. MOLLER, citizens of the United States, residing at East Orange, in the county of Essex and State of New Jersey, and residing at Jersey City, county of Hudson, and State of New Jersey, respectively, have invented certain new and useful Improvements in Underhang Framework or Chassis Construction; and we do hereby declare the following to be a full, clear, and exact description of the invention, such as will enable others skilled in the art to which it appertains to make and use the same, reference being had to the accompanying drawings, and to characters of reference marked thereon, which form a part of this specification.

This invention relates, generally, to improvements in the underhang frame-work or chassis-constructions for railway cars; and, the present invention has reference, more particularly, to a novel construction of underhang frame-work or chassis-construction for electric street-railway cars or electric busses with a view of providing in addition to a novel arrangement and construction of the devices and parts comprising the frame-work, a novel means for hanging the truck-springs to said frame-work, and to provide also in connection therewith a novel arrangement and construction of journal-boxes and wheels for the same.

The present invention, therefore, has for its principal objects to provide a novel and simply-constructed underhang frame-work or chassis-construction, generally, for railway cars, and more particularly for electric street-railway cars or electric busses; and, the invention has for its further object to provide in connection with the frame-work, a novel means for hanging the truck-springs thereto, and also to provide a novel and simple arrangement and construction of journal-boxes and wheels for the same, all of which will more fully appear in the following specification.

Other objects of the present invention not at this time more particularly enumerated will be clearly understood from the following detailed description of the present invention.

With the various objects of the present invention in view, the said invention consists, primarily, in the novel underhang

frame-work or chassis-construction for railway cars, and especially for electric street railway cars or electric busses, as well as in the novel means for hanging the truck-springs to said frame-work, and in the novel arrangement and construction of journal-boxes and wheels therefor; and, the invention consists, furthermore, in the general arrangements and combinations of the various devices and parts, as well as in the details of the construction of the said parts, all of which will be more fully described in the following specification, and then finally embodied in the clauses of the claim which are appended to and which form an essential part of the said specification.

The invention is illustrated in the accompanying drawings, in which:—

Figure 1 is a plan view of the main frame or chassis-construction for an electric street railway car, said view showing one embodiment of the principles of the present invention; and Fig. 2 is a side elevation of the same, the frame-work shown in said figures being ordinarily termed the under or body-frame, and the lower truck-frame carrying the springs, journal-boxes, wheels and actuating mechanism usually employed with the truck-frame, being omitted from said views.

Fig. 3 is a plan view of the truck-frame and its parts, said drawing being made on a larger scale, with the under or body-frame, shown in said Figs. 1 and 2, omitted from said view; and Fig. 4 is a longitudinal vertical sectional representation of the truck-frame, showing in connection therewith, and also in longitudinal vertical section, the main central portions of the said under or body-frame.

Fig. 5 is a side elevation of one of the journal-boxes, and fragmentary portions of the frame to which it is secured, and of the spring mounted upon said frame; and Fig. 6 is a detail transverse vertical sectional representation of the same, showing in connection therewith a fragmentary portion of a car-wheel axle mounted in said box, and a transverse vertical sectional representation of portions of one of the car-wheels mounted upon said axle.

Similar characters of reference are employed in all of the said above described views, to indicate corresponding parts.

Referring now to the several figures of the drawings, the reference-characters 1 and 2

105

110

indicate the longitudinally extending side-members or bars of the lower or main body-frame, the said members being usually in the form of channel-irons or bars, said side-members or bars 1 and 2 being suitably tied, in any desired manner, by an arrangement of suitably disposed cross-bars 3, 4, 5, 6, 7 and 8, said cross-bars being also in the form of channel-irons, or the like. The respective end cross-bars 3 and 8 are usually tied with the respective cross-bars 4 and 7, and with the side-members or bars 1 and 2, by means of braces, as 9 and 10, to provide the platform-sections of the said frame-work, as will be clearly evident. The respective platform-sections, thus provided, have suitably secured to the end-portions of the respective side-bars or members 1 and 2 of the frame-work, and located at the proper sides thereof, steps as 11 and 12 of any desired and suitable construction.

As shown in Figs. 1 and 2 of the drawings, extending laterally from the said longitudinally extending side-bars or members 1 and 2, and suitably secured thereto in any well-known manner, are suitably constructed brackets 13, or other suitable members, which carry the usual posts or uprights 14 of the body members 15 of the car, substantially as indicated in said Fig. 1.

Connected with and suitably disposed between the cross-bars 5 and 6, at the proper location, are supporting members 16 and 17 which carry a compressed air-mechanism or cylinder 18 of any usual construction, and which is provided with the usual actuating arms or levers 19 and 20, pivotally mounted, as at 21 and 22, upon the supporting member or bar 17, and with which levers 19 and 20 may be operatively connected, in any usual manner, the actuating links or rods 23 and 24, see Fig. 4 of the drawings of the usual brake-shoe actuating members 25 and 26, for forcing the brake-shoes 27 out of or into engagement with the peripheral surfaces of the wheels 28 mounted upon the car-wheel axles 29.

Referring now once more to Fig. 1 of the drawings, it will be seen, that the respective cross-bars 4 and 5, and 6 and 7, are each respectively provided with a pair of suitably-constructed bearing-members or brackets, as 30, 31, 32 and 33, the members or brackets 30 and 32 carrying shackle-bolts 55 or pins, as 34, and the members or brackets 31 and 33 carrying shackles 35 which are pivotally connected with said members or brackets 31 and 33 by means of other shackle-bolts or pins 36, substantially as illustrated in Fig. 4 of the drawings, and for the purposes to be hereinafter more fully described. Employed in connection with the heretofore described frame-work and the various elements thereof is the truck-frame 60 and the journal-boxes thereof, as well as va-

rious other elements used with the same, shown in Figs. 3, 4, 5 and 6 of the drawings.

The said truck-frame is more particularly illustrated in said Figs. 2 and 3, and the same comprises a pair of longitudinally extending side-members or bars 37 and 38, the said members being also usually in the form of channel-irons or bars, and being suitably tied, in any desired manner, by an arrangement of cross-bars 39 and 40. At the respective end-portions, the said side-members or bars 37 and 38 have secured thereto by means of bolts 41, or other suitable fastening means, carrier-elements or members, as 42, formed with the socketed portions 43 for the reception of the end-portions of laterally extending end-rods, as 44.

Each carrier element or member 42 is further provided with a perforated portion 45, and pivotally connected with each portion 45, by means of a pin 46, is an oscillating link 47, each pair of said links carrying upon their lower ends suitably formed extensions, as 48, upon which are secured by means of bolts 49, or other suitable fastening means, the respective end-portions of brake-beams 50 which carry the previously mentioned brake-shoes.

As shown more particularly in Fig. 3 of the drawings, each brake-beam 50 comprises the divided parts or members 52 and 53, and extending across the open central portion 51 of said parts or members 52 and 53, by being secured to the member 53 by means of bolts 54 and to the part 52 by means of an embracing end-portion, as 55, are flanged bearing-plates 56 carrying suitably disposed pivot-pins 57 upon which the previously-mentioned brake-shoe actuating members 25 and 26 are oscillatorily mounted. The lower end-portions of the said members 25 and 26 have connected therewith in any usual manner, by means of bolts or pins 58, the perforated end-portions of a pair of adjusting rods 59, which are adjustably connected by means of a turn-buckle 60, or other suitably constructed adjusting means may be used, as will be clearly evident.

Referring now to Figs. 4, 5 and 6 of the drawings, it will be seen that the previously mentioned longitudinally extending side-members or bars 37 and 38 are each provided at the respective locations, where the car-wheel axles are to be placed, with suitably formed plates 60 disposed upon the upper surface-portions of said side-members or bars and secured thereto by means of bolts or screws, as 61, in a manner to be presently set forth. As shown, these plates 60 are each provided with a pair of upwardly extending and centrally disposed side-flanges, as 62, for the placing therebetween of the centrally disposed leaf-retaining member or band 64 of the leaf-spring 63, 130

In addition, each plate 60 is provided with a plurality of tubular bosses 65, in which are disposed and secured in place by means of nuts, as 66 and 67, the screw-threaded shank-portions 68 of suitably-formed spring-embracing shackles, as 69, substantially as shown in said Figs. 5 and 6 of the drawings; and whereby the respective springs 63 are longitudinally disposed directly above the 5 respective side-members or bars 37 and 38, as will be clearly evident. The looped end-portions 70 of said springs 63 are operatively connected with the pins or bolts 34 of the respective brackets 30 and 32, and the 10 15 correspondingly looped end-portions 71 of the springs 63 are operatively connected with the pins or bolts 72 with which the previously-mentioned shackles 35 are provided, thus providing each spring with a 20 25 three-point suspension. From an inspection of said Figs. 5 and 6, it will be seen, that there is disposed between the upper and lower flanged portions of the said side-members or bars 37 and 38, suitably-formed 30 35 supporting or bracing elements, as 73, provided with tubular bosses 74, or other suitable means, for the reception of the previously mentioned bolts or screws 61, said bolts being passed through correspondingly located holes in said upper and lower 40 45 flanged portions, and through correspondingly placed holes in the upper body-member 75 of the corresponding journal-box, the body-member 75 of each journal-box thus 50 55 being secured in its fixed position against the under face of the lower flanged portion of the respective side-member or bar 37 or 38, by means of nuts 76 which are secured upon the projecting screw-threaded shank- 60 65 portions of the said bolts or screws 61, substantially as illustrated in said Fig. 5 of the drawings. The said body-member 75 is preferably formed with the upwardly extending embracing flanges 77 and 78, and 65 70 the semi-circular hub-portions 79 and 80. The reference-character 81 indicates a lower member of the journal-box, which is formed with a lubricant-receiving chamber 82, and upon its opposite sides has the semi-circular hub-portions 83 and 84. The two members 75 and 81 are suitably connected in their assembled relation, as shown in Fig. 5 in any usual manner, by means of screws or bolts 85 and nuts 86. Connected with the 75 80 body-member 81 and extending angularly therefrom, in an upward direction, is a chambered member 87 in communication with the main chamber 82 for supplying the latter with a lubricant, the said member 87 being provided with a suitably formed closure as 88. Disposed within the assembled body-members 75 and 81 of each journal-box are suitably formed brasses or bearing-sleeves 89 in which the journal-portions of 85 90 95 the car-wheel axles are adapted to revolve,

said members 89 being also suitably flanged, as at 90.

Suitably mounted upon the end-portions of the said axles, by pressure or otherwise, are hubs 91, each hub being provided with 70 annular flanges 92 and 93 which are respectively formed with the off-set portions 94 and 95. Suitably disposed in the said off-set portions 94 and 95 of the respective flanges 92 and 93 are the centrally located 75 openings of a pair of disks 96 and 97, which are respectively provided with the inwardly bent portions 98 and 99 so as to form at various locations, and concentrically with the central longitudinal axis of the car-wheel axle, a series of bearing portions 100 and 101, located near the outer peripheral or circumferential marginal edges 102 and 103 of the said disks 96 and 97. The disks 96 are securely held in place by means of 80 85 bolts 104 and nuts 105, the said bolts and nuts being also employed for securing against the said assembled parts, a closing plate, as 106, and as clearly shown in Fig. 6 of the drawings. In a like manner the 90 95 said disks 97 are secured in their operative positions against the flanges 93 of the respective wheel-hubs 91 by an arrangement of rivets 107, or other suitable fastening means.

As shown the depressed portions 100 and 101 which provide the above-mentioned bearing portions, are centrally perforated, as at 108 and 109, for the arrangement therein of pintles 110, which are secured in 100 place by means of their heads 111 and nuts 112, as shown, and have mounted thereon suitably formed cushion-hubs 113 which are preferably circumferentially serrated, as at 114, for operatively mounting upon each 105 cushion-hub a rubber cushion 115. Encircling each cushion 115 is a metallic cushion-rim 116, preferably of the general configuration illustrated in said Fig. 6. The said cushion hubs 113, and the cushions 115 110 and rims 116 are concentrically disposed about a central ring 117, with which the several rims 116 are disposed in a manner that the said ring 117 is operatively held against displacement. 115

In tangential contact with the said several cushion-rims 116 is a main engaging ring or felly band, as 119, upon the outer peripheral surface of which is mounted and suitably secured thereon by pressure, or otherwise, a wheel-tread 118, of any usual conformation in cross-section. 120

As shown in said Fig. 6, the previously mentioned wheel-hub 91 is also annularly flanged, as at 120, the said annular flange 125 120 extending into the open portion of the hub-portions 80 and 94. The previously mentioned hub-portions 79 and 83, and 80 and 84, are internally recessed, as 122, for the reception therein of suitable packings 130

121, of felt or other suitable material. Between the various parts designated by the reference-characters 90 and 110, and concentric with the car-wheel axle is a horn-fiber washer 123. It will be evident, however, that this washer may be made of any other suitable material.

From the foregoing description of the present invention, it will be noted, that we 10 have produced a novel and simply constructed underhang frame-work or chassis- construction which is especially adapted for street railway cars, but which may be put to other uses, as in the construction of electric busses, and similar vehicles.

We are, further, fully aware that changes 20 may be made in the general arrangements and combinations of the various devices and parts, as well as in the details of the construction of the said parts, without departing from the scope of the present invention as set forth in the foregoing specification, and as defined in the clauses of the claims which are appended to the said specification. Hence, we do not limit our present invention to the exact arrangement and combination of the devices and parts as described in the said specification, nor do we 30 confine ourselves to the exact details of the construction of the said parts, as illustrated in the accompanying drawings.

We claim:—

1. In an underhang frame-construction for railway-cars, and the like, a main body-frame consisting of a pair of longitudinally extending side-members, a plurality of laterally extending cross-bars between said side-members and secured at their end-portions to the respective side-members, and a plurality of brackets extending laterally and outwardly from said side-members for securing thereto the frame-work of the car-body, brackets likewise secured to others of said cross-bars, a plurality of leaf-springs, and means connected with the said 50 last-mentioned cross-bars for pivotally mounting the respective end-portions of said leaf-springs with relation to said frame-body.

2. A truck-frame for railway cars, and the like, consisting of a pair of longitudinally extending side-members, cross-bars between said side-members and secured at their end-portions to the respective side-members, and journal-boxes secured to said 60 side-members, each journal-box comprising an upper and a lower body-member constructed to receive the journal-end of an axle, means for securing said upper and lower body-members about such journal-end, flanges extending upwardly from said

upper body-member in embracing relation with the side-member of the truck-frame and means for securing said upper body-member to said side-member.

3. A truck-frame for railway cars, and the like, consisting of a pair of longitudinally extending side-members, cross-bars between said side-members and secured at their end-portions to the respective side-members, and journal-boxes secured to said side-members, each journal-box comprising an upper and a lower body-member constructed to receive the journal-end of an axle, means for securing said upper and lower body-members about such journal-end, flanges extending upwardly from said upper body-member in embracing relation with the side-member of the truck-frame and means for securing said upper body-member to said side-member, consisting of a bracing element provided with tubular bosses, said tubular bosses being in alinement with bolt-receiving holes with which the side-members of the truck-frame and the upper body-members of the journal-boxes are provided, and tightening bolts in said alined holes and tubular bosses.

4. A truck-frame for railway-cars, and the like, comprising longitudinally extending side-members, leaf-springs mounted upon said side-members, and means for securing said springs upon said side-members, each spring-securing means consisting of a plate adapted to be secured upon the upper surface of a side-member, embracing flanges extending in upward direction from said plate for the reception therebetween of the leaf-retaining band of the spring, said plate being also provided with laterally extending tubular bosses, shackles embracing the leaves of said springs, said shackles having screw-threaded shank-portions in said tubular bosses and extending therefrom, and nuts upon said screw-threaded shank-portions.

5. A truck-frame for railway cars, and the like, comprising longitudinally extending side-members, leaf-springs mounted upon said side-members, and means for securing said springs upon said side-members, each spring-securing means comprising a bracing element provided with tubular bosses, and a plate disposed upon the upper surface of said side-member, said side-member and plate being provided with bolt-receiving holes in alinement with the tubular bosses of said bracing element, tightening bolts in said alined holes and tubular bosses, embracing flanges extending in upward direction from said plate for the reception therebetween of the leaf-retaining band of the spring, said plate being also provided with tubular bosses, shackles embracing the leaves of said springs, said shackles having screw-threaded shank-portions in said last- 130

mentioned tubular bosses and extending therefrom, and nuts upon said screw-threaded shank-portions.

6. A truck-frame for railway cars, and the like, consisting of a pair of longitudinally extending side-members, cross-bars between said side-members and secured at their end-portions to the respective side-members, and journal-boxes secured to said side-members, each journal-box comprising an upper and a lower body-member constructed to receive the journal-end of an axle, means for securing said upper and lower body-members about such journal-end, flanges extending upwardly from said upper body-member in embracing relation with the side-member of the truck-frame, and means for securing said upper body-member to said side-member, consisting of a bracing element provided with tubular bosses, said tubular bosses being in alinement with bolt-receiving holes with which the side-members of the truck-frame and the upper body-members of the journal-boxes are provided, and tightening bolts in said alined holes and tubular bosses, combined with a wheel mounted upon said journal-end of the axle, consisting of a hub provided with annular flanges, a pair of disks, and means for securing said disks to said annular flanges, said disks being provided with a plurality of depressed bearing-portions, a bolt connected with and extending across the space between each pair of bearing-portions, a cushion hub mounted upon each bolt, a cushion surmounting each hub, a rim surmounting each cushion, a main central ring, and an outer engaging ring, between which two rings the said cushion-hubs and their elements are disposed, and a wheel-tread upon said outer engaging ring.
7. A truck-frame for railway cars, and the like consisting of a pair of longitudinally extending side-members, cross-bars between said side-members and secured at their end-portions to the respective side-members, and journal-boxes secured to said
- side-members, each journal-box comprising an upper and a lower body-member constructed to receive the journal-end of an axle, means for securing said upper and lower body-members about such journal-end, flanges extending upwardly from said upper body-member in embracing relation with the side-member of the truck-frame, and means for securing said upper body-member to said side-member, consisting of a bracing element provided with tubular bosses, said tubular bosses being in alinement with bolt-receiving holes with which the side-members of the truck-frame and the upper body-members of the journal-boxes are provided, and tightening bolts in said alined holes and tubular bosses, combined with a wheel mounted upon said journal-end of the axle, consisting of a hub provided with annular flanges, a pair of disks, and means for securing said disks to said annular flanges, said disks being provided with a plurality of depressed bearing-portions, a bolt connected with and extending across the space between each pair of bearing-portions, a cushion hub mounted upon each bolt, a cushion surmounting each hub, a rim surmounting each cushion, a main central ring, and an outer engaging ring, between which two rings the said cushion-hubs and their elements are disposed, and a wheel-tread upon said outer engaging ring.

In testimony that we claim the invention set forth above we have hereunto set our hands this 31st day of January, 1920.

HERSHEL A. BENEDICT.
EDWARD M. MOLLER.
